(57) CLAIM

The ornamental design for a tanning lotion bottle, as shown and described.

DESCRIPTION

FIG. 1 is a perspective view of the tanning lotion bottle.

FIG. 2 is a front view of the tanning lotion bottle.

FIG. 3 is a rear view of the tanning lotion bottle.

FIG. 4 is a right view of the tanning lotion bottle, the left side view is symmetric; and,

FIG. 5 is a top view of the tanning lotion bottle.

The broken line showing of the indicia is for illustrative purposes only, and forms no part of the claimed design.
